UNITED STATES PATENT OFFICE

2,229,286

PAPER FEEDING AND CUTTING MEANS

Israel C. Gellman, Rock Island, Ill., assignor to
Gellman Manufacturing Company, Rock Island,
Ill., a corporation of Illinois

Original application March 8, 1937, Serial No.
129,561. Divided and this application October
29, 1937, Serial No. 171,754

13 Claims. (Cl. 93—2)

This invention pertains to wrapping machines, and more particularly to paper feeding means for use with bread wrapping machines, and is a division of my pending United States application Serial No. 129,561, filed March 8, 1937.

It is an object of the present invention to provide a simple web feeding mechanism which includes brackets for supporting a roll of paper or webbing, rollers for feeding the webbing, a manual crank, and a unidirectional drive means between the crank and rollers.

Another object is the provision of a feeding mechanism for attachment to a wrapping machine having a reciprocable wrapping carriage, and a cutting device having sliding support partly on the feeding means and partly on the machine below the carriage, and cam means on the carriage for operating the cutting means once for each reciprocation of the carriage.

It is another object to provide eccentric adjustable bearing means for the roller mechanism.

It is a further object to provide a simple means for determining the length of the effective stroke of the crank, and hence of the length of webbing fed at each operation of the crank.

A further object is the combination with means for feeding paper webbing toward a wrapping device adapted to utilize the webbing in wrapping operation, of means for shearing the webbing automatically and actuated by said wrapping device once during each reciprocation thereof, the shearing means being mounted to cut the webbing transversely of its length and being further mounted to shift in the direction of movement of the webbing and the wrapping device into positions of adjustment so that different lengths of webbing may be cut to accommodate articles of different size.

Other novel aspects and objects of the invention, both in construction and operation, will appear as the following description proceeds in view of the drawings, in which:

Fig. 1 is a side elevation of the web feeding structure;

Fig. 2 is a sectional side view similar to Fig. 1, but including the cutting mechanism;

Fig. 3 is a fragmentary vertical section of the manual drive means viewed along lines 3—3 of Fig. 1;

Fig. 4 is a fragmentary inside elevation of part of the manual drive means looking in the direction of lines 4—4 of Fig. 3;

Fig. 5 is a top plan fragment of the feed apron and cutting means looking down along lines 5—5 of Fig. 2;

Fig. 6 is a side elevational detail of the cutter, as seen on line 6—6 of Fig. 5;

Fig. 7 is a front vertical section through part of the cutter, as seen along lines 7—7 of Fig. 6;

Fig. 8 is a side section detail of the cutting means taken along lines 8—8 of Fig. 5; while

Fig. 9 is a sectional detail through the cutter mounting means along lines 9—9 of Fig. 6.

As viewed in part in Fig. 2, a bread wrapping machine of a type for which the paper feed is especially suited is shown to include a main frame 24 having a reciprocable bread elevator 28 which receives conveyed bread from a member 53 and is adapted to elevate a loaf against a piece of wrapping paper yieldably stretched across the path of the elevator by tautening means including a roller 91 mounted in bracket means 93 so as to effect a partial wrapping of the loaf, further wrapping being accomplished by a reciprocable wrapping carriage 88 which moves through agency of reciprocally driven links 142 in timed relation to the elevator to withdraw the loaf therefrom, and also effect further partial wrapping, as set forth in detail in the aforesaid pending application.

As seen in Fig. 1, the paper feed mechanism includes a pair of spaced uprights in the form of somewhat triangularly shaped castings 200 mounted at an end of the frame 24.

A pair of paper rolls 201 are supported on rollers 202, which are cradled in slots 203 cast in the upper corner portions of the frame 200. The paper webs 204 may both be fed over an idling roller 205 journaled between the brackets 200 and thence between a master feeding roller 206, and presser rollers 207 likewise journaled between the brackets 200 (Fig. 2). The presser rollers 207, however, are provided with an eccentric stud journal 208 pivotally supported on the brackets 200 and provided with a handle portion 209 and a set screw 210, by means of which the several rollers 207 may be pivoted toward and away from the master feed roller 206 and locked in a desired position.

The pressure rollers 207 are spaced apart suitably and extend into a plurality of edgewise slots 211 (Fig. 3) formed in a feeding apron 212 which is anchored at its rearward or left-hand extremity as seen in Fig. 2, to a cross member 213 and which extends arcuately downward beneath the knife supporting bracket 214 to a point confronting the rearmost edge of the stationary cutting knife 215 (Figs. 2, 6 and 8).

The master feed roller 206 is provided with a gear 216 which meshes with a driving gear 217.

rotatable by a reciprocably operable crank 218 journaled in one of the brackets 200, and having an offset arm 219 which is adapted to abut against a movement limiting pin 220 movable in an arcuate slot 221 provided in the frame 200. The pin 220 may comprise two threaded portions so that it may be clamped or screwed into position in the arcuate slot and thus stop the movement of the crank 218 at any desired position. 5 In this way the distance which the master roller 206 is rotated determines the length of paper which will be fed from the rolls 201.

The fragmentary elevation shown in Fig. 4 illustrates the crank mechanism on the inner side 15 of the main bracket 200 and includes a ratchet 222 on the crank spindle, and a pair of sprung-urged pawls 223 engageable with the ratchet and which permit the initial movement of the crank 218 in an anti-clockwise direction, but which 20 effect a driving engagement with the gear 217 when the crank is returned in a clockwise direction (Fig. 1) for each feeding operation.

The knife supporting structure includes a yoke-shaped frame 224 (Figs. 5 and 6) the left-hand 25 free ends of which are pivotally mounted, as at 225, to a cross bearer bracket 226 which extends between the upright sides of the main supporting brackets 200, and which is engaged at its outermost extremities by a set screw 227 slideable in an 30 elongated slot 228 in the support 200. A front bearer 229 is joined with the rear bearer 226 by longitudinally extensive straps 230 (Fig. 6). The front bearer 229 is slidably supported at its ends 35 on shelves 112 formed in frame 24 and engages the offset end portions 231 of the elongated rails 232 (Figs. 5 and 8) which are secured to the main longitudinal rails 89 inside of the main frame by means of set screws 233 extending through longitudinal slots 234 in the supporting rails 232. The 40 upturned end portions 231' of the supporting rails 232 fit into slots in the front cross bearer 229.

In order to adjust the position of the knife carrier, it is simply necessary to loosen the set screws 227 (Figs. 5 and 9) and the screws 233, 45 whereupon the rear and front bearers 226 and 229, together with the supporting rails 232, may be moved forwardly or backwardly to any desired position.

The front cross bar of the knife frame 224, as 50 seen in Figs. 5 to 8, is provided with a plurality of spaced, extending bosses 235, the outermost ones of which are provided with a slot in which are seated rollers 236 engageable by cam fingers 237 (as in Figs. 2 and 8) extended from the rear of the inner folding carriage 88 when the latter is moving through the backward portion of its travel.

The centrally or inwardly located extended 60 bosses 235' are provided with set screws 238 which serve to urge tension springs 239 against the movable knife elements 240 against the laterally extensive cutting edge of the stationary knives 215, it being observed that the movable knives 240 65 are two in number (Fig. 7), being separated from one another at substantially the midpoint of the frame, and being pivotally attached to the latter by means of hinges 241. It will be observed that the cutting edge of the knives is relieved inwardly 70 from the outermost extremities of the blade toward the centers thereof, for the purpose of providing an advancing cut across the sheet as the knife frame descends.

At the outermost forward (right hand) 75 corners of the frame 224, there are bosses 235'' pro-

vided with a vertical spring well 242 in which are seated springs 243, seated on screw studs 244 extending through the stationary knives 215. These springs serve to return the knife frame to its raised position after each cutting operation. 5

In Fig. 5 (and also Figs. 6 to 8), it will be observed that an intermediate paper support is provided between rail parts 231—232 for the sheet of wrapping paper, and this support takes the form of an extensible pan or apron which includes a bracket 260 having a lower offset edge part 261 (Fig. 8) which bends down below the bottom of the front bearer 229 of the knife frame, and is secured to the latter by means such as the screws 264. The upper part 261' of this apron 10 structure overlies a frame cross arm 265 and has adjacent its right-hand end, as seen in Fig. 8, an extensible part 262 (see also Fig. 7) slidably supported on opposite flange members 263 screwed or otherwise attached to the bottom of the main 15 bracket part 260.

All of the paper feed chutes and aprons are 20 preferably provided with longitudinally extensive ribs 212' (on the apron 212, Figs. 3 and 5). By this means friction resistance to the movement 25 of the paper is reduced and at the same time the paper is stiffened for more efficient feeding and positioning.

In order to prevent slippage of the wrapping 30 paper, which is frequently a waxed paper, between the master feed roller 206 and the presser rollers 207, the latter are driven with and by the master roller 206 by means of gear teeth 217a which mesh with teeth 216a provided on the presser roller shaft at the right-hand interior side of the paper roll frame 200, as seen in Fig. 2. In this manner when the master roller 206 is turned by the crank 218 or other means, the presser rollers 207 rotate therewith through the medium 35 of the meshed gearing 216a—217a, thus assuring 40 a positive feeding movement of the paper web.

The operator has merely to rotate the crank 218 in an anti-clockwise direction, having previously set the pin 220 to determine the length of stroke or amount of paper to be fed, and then return the crank in the opposite or clockwise direction so as to rotate the gear 217 through the medium of the ratchet mechanism 222—223 (Figs. 1 and 4). The result of this operation is 50 to rotate the master rollers 206 and feed a portion of the paper web (two thicknesses being optionally used in the embodiment shown) downwardly into the apron 212, and thence beneath the knife carrying frame 214 and above the point of issue 55 of the elevator 28.

It may be observed that the advancing paper is slid onto the spaced rails 89, between which the elevator 28 rises (Figs. 2 and 5). The paper is tautened by means of presser bars 95 working 60 in slots 89' on rails 89, and urged upwardly by spring means 96 which press the paper up against adjustable cross rollers 91 beneath the carriage 88 (roller 91 being adjustable by reason of its 65 slideable mounting bracket 93).

Meanwhile, it may be assumed that the machine has been set into wrapping operation by the master control lever 38, and that the inner carriage 88 moves backwardly before the folding operation and causes the cam fingers 237 70 thereon (Fig. 2) to ride onto the rollers 236 on the frame 224, thus pivoting the latter downwardly against the tension of the return springs 243 (Fig. 8). In this manner the movable knife member 240 will bear against the paper sheet 75

and against the stationary knife member 215 and shear the paper, whereupon the carriage 88 having again moved forward will permit the knife to rise ready for the next cutting operation, 5 which will be a repetition of the foregoing procedure.

I wish it to be understood that I do not desire to be limited to the exact details of construction shown and described, for obvious modifications will occur to a person skilled in the 10 art.

Having thus described my invention, what I claim as new and desire to protect by Letters Patent is:

15 1. In a wrapping machine, the combination, with a reciprocable wrapping member therein of adjustable means for feeding predetermined lengths of webbing in the direction of reciprocation of said wrapping member and into wrapping position relative to the latter, web severing means extending transversely of said webbing near one of the terminal positions of said wrapping member, means mounting said severing means for reciprocable adjusting movement in 20 the direction of movement of said webbing, and means on said wrapping member arranged for cooperation with said severing means to actuate the latter in web severing operation when the wrapping member moves into a certain position relative to said terminal position.

2. In a machine of the class described including spaced upright bracket means for supporting paper supply roller means, a cutting device including a pivoted frame carrying a knife element and bearer means therefor having partial horizontally sliding support on said bracket means and sliding support on means in said machine, whereby the cutting position of said knife element may be adjusted horizontally.

30 3. In a machine of the type described including a frame, a reciprocable wrapping carriage and drive means therefor, paper feeding means including a pair of brackets mounted in oppositely spaced upright position at an end of said frame substantially opposite one of the terminal positions of said carriage, paper supply roller means journaled on said brackets for rotation about an axis transverse to the direction of reciprocation of said carriage, feed roller means 35 journaled on said brackets collaterally with said supply roller means and operable to feed paper webbing therefrom toward said carriage for utilization by the latter, means for actuating said feed roller means, and web severing means co-50 acting with said carriage and having horizontally sliding adjustable support on said brackets for movement toward and away from said carriage.

4. In a machine of the class described, paper feed mechanism including a pair of brackets mounted in opposite upright position on said machine, said brackets each having a horizontally extensive top arm joined to convergently sloping arms which converge in a lower mounting head attached to said machine, each bracket having means near the juncture of the horizontal and sloping arms providing journals for paper supply rollers, feed roller means journaled on said brackets in the region of said lower mounting head for rotation collaterally of said supply roller means, and drive means mounted on said lower head portion for driving said feed roller means, each of said brackets having aligned horizontal slots in the lower mounting head portion 55 thereof and providing support for a horizontal

paper web severing means cooperable with said machine.

5. In a web feeding and shearing mechanism, means for supporting a supply of webbing, mechanism for feeding said webbing in a substantially horizontal plane into a predetermined position, and shearing mechanism including shear supporting means mounted for movement horizontally back and forward in the direction of movement of said webbing toward said predetermined position, and a movable shear member carried by said supporting means and arranged for movement from a normally raised position above the plane of movement of said webbing into shearing engagement transversely across 15 the latter, and means for moving said shear in shearing action.

6. In a device of the class described including a reciprocable member with respect to which various lengths of webbing are to be fed, means for feeding webbing into operative relation with respect to said reciprocable member, shear supporting means mounted for movement toward and away from said reciprocable member in the direction of movement of said webbing, shear 20 means mounted on said supporting means for movement toward and away from the plane of said webbing, means yieldably urging said shear means into a normal position away from the webbing, together with means coacting with said reciprocable member when the latter is moved into a certain position to move said shear means into shearing engagement with said webbing.

7. In a sheet feeding and shearing device including means for feeding sheeting into a certain 35 position, shearing mechanism comprising a support mounted for movement back and forth in the direction of movement of said sheeting toward said position, means for securing said support in positions of adjustment relative to said 40 position, stationary shear means carried by said support and disposed on one side of the path of movement of said sheeting, movable shear means carried by said support on the opposite side of said path of the sheeting and movable toward 45 and away from said stationary shear means, together with mechanism for moving said movable shear means toward and away from said stationary shear means for cooperation with the latter to cut different lengths of sheeting dependent 50 upon the position of adjustment of said support with respect to said particular position.

8. In a paper feeding and cutting mechanism, paper supporting means onto which paper is to be fed, means for feeding a paper webbing onto said 55 supporting means, and adjustable web shearing means including a knife carrier and means mounting the same at one side opposite said paper supporting means for adjusting movement toward and away from the latter, means support- 60 ably associated with said paper supporting means for supporting said knife carrier at its side adjacent the paper supporting means, and knife means arranged on said carrier for actuation to sever said webbing after the same is fed 65 onto said supporting means and in lengths depending upon the adjusted position of said carrier relative to said supporting means.

9. In a wrapping machine of the class described including a reciprocable wrapping member and 70 adjustable means for feeding different lengths of wrapping paper in a continuous web in the general direction of reciprocation of said wrapping member into a wrapping position relative to the latter, web severing means mounted near one of 75

- the terminal positions of said reciprocable wrapping member and including severing elements extending transversely of the webbing, and means mounting said severing means for reciprocable 5 adjusting movement in a direction toward and away from said terminal position in the direction of movement of said webbing and reciprocable wrapping member whereby different lengths of wrapping paper may be severed from said web 10 dependent upon the position of adjustment of the severing means relative to said terminal position, said severing means being adapted to be actuated by means coacting with said reciprocable wrapping member.
- 15 10. In a web feeding and shearing mechanism, means for supporting a supply of webbing, mechanism for feeding said webbing in a substantially horizontal plane into a predetermined position, and shearing mechanism including shear supporting means mounted for movement horizontally back and forward in the direction of movement of said webbing toward said predetermined position, and a movable shear member carried by said supporting means and arranged for movement from a normally raised position above the plane of movement of said webbing into shearing engagement transversely across the latter, said movable shear member being adapted to coact with reciprocable wrapping means which 20 moves back and forth relative to said predetermined position in the direction of movement of the webbing, to actuate said movable shear once during each reciprocation of said wrapping means.
- 25 11. In a sheet feeding and cutting mechanism for use in a wrapping machine having wrapping instrumentalities adjustable to accommodate articles of different size requiring different lengths of wrapping material, the combination of means 30 for feeding a web of sheet wrapping material into a predetermined position for utilization with said wrapping instrumentalities, web shearing means cooperable with one of said instrumentalities for operation to shear said webbing periodically in 35 timed relation to the wrapping operation of said instrumentalities, said web shearing means including a movable cutting member extended transversely of said webbing for movement toward and away from the latter in shearing oper- 40
- ation, and means adjustably mounting said movable cutting member for movement back and forth toward and away from said predetermined position in the direction of movement of said webbing, whereby different lengths of the latter 5 may be cut as aforesaid.
- 45 12. In a machine of the class described including a reciprocable carriage to perform an operation upon a sheet, sheet feeding and shearing means comprising, in combination, mechanism 10 for feeding a web of sheet material into position beneath said carriage by movement in one of the directions of reciprocal movement of said carriage, and web shearing means including a cutting device arranged and constructed to coact 15 with said carriage for movement by the latter into shearing engagement with the webbing once during each reciprocation of the carriage, and means adjustably mounting said cutting device for movement back and forth in the direction of 20 movement of said carriage, whereby the length of web cut as aforesaid may be changed, said carriage coacting with said cutting device to actuate the latter in all positions of adjustment as aforesaid. 25
- 50 13. In a machine of the class described including a reciprocable wrapping device arranged for movement to effect wrapping operations upon cut lengths of sheet material, the combination of sheet feeding and cutting means comprising 30 mechanism for feeding a web of sheet material in one of the directions of reciprocation of the wrapping device into positions for utilization with the latter, a cutter support mounted for adjusting movement in the directions of reciprocation 35 of said wrapping device, a movable cutter mounted on said support for movement toward and away from the plane of said webbing transversely of the latter into and out of cutting engagement therewith, and means operatively associat- 40 ing said wrapping device and said movable cutter to effect movement of the latter into cutting engagement with said webbing in a certain timed relation to the movement of said wrapping device, said last-mentioned means operatively as- 45 sociating the wrapping device and movable cutter being arranged to actuate the cutter as aforesaid in all positions of adjustment thereof.

ISRAEL C. GELLMAN.
